UNITED STATES PATENT OFFICE.

GUSTAV B. PETSCHÉ, OF PHILADELPHIA, PENNSYLVANIA, ASSIGNOR TO SOUTHWARK FOUNDRY AND MACHINE COMPANY, OF PHILADELPHIA, PENNSYLVANIA, A CORPORATION OF PENNSYLVANIA.

BLOWING-ENGINE OR COMPRESSOR.

No. 891,858.

Specification of Letters Patent.

Patented June 30, 1908.

Application filed August 4, 1906. Serial No. 329,176.

To all whom it may concern:

Be it known that I, GUSTAV B. PETSCHÉ, a subject of the Emperor of Germany, residing in the city and county of Philadelphia, in the State of Pennsylvania, have invented certain new and useful Improvements in Blowing-Engines or Compressors, of which the following is a true and exact description, reference being had to the accompanying 10 drawings, which form a part thereof.

My invention relates to blowing engines or compressors and has for its object to provide an engine of this kind having the maximum port space for both the admission and delivery of the air.

The leading feature of my invention consists in forming the cylinder with a circumferential series or set of ports extending through its side at each end, and with a set 20 of ports extending through each cylinder head, the two sets of ports at each end of the cylinder forming, the one, admission ports, and the other the delivery ports, and in providing valves controlling said ports and operating connections for the valves by which the admission valves are opened and closed and the delivery valves are closed in definite relation to the movement of the compressing piston in the compressing cylinder, and in 30 providing means by which the delivery valve at each end of the cylinder is opened when the ratio of the pressure in the corresponding end of the cylinder to the pressure in the receiver into which the pressure discharges 35 rises to a predetermined value. By preference, I employ an oscillating annular valve ring with ports adapted to register with the circumferential ports at each end of the cylinder to control the circumferential ports.

40 Other features of my invention will be best understood as described in connection with the drawings in which I have illustrated an engine equipped with my invention in what I believe to be its most advantageous form 45 and in which

Figure 1 is an end view of my engine. Fig. 2 is a side elevation thereof, the half of the view at the left hand side being shown in central vertical section. Fig. 3 is a plan view of 50 the engine. Fig. 4 is an end elevation taken on the section line 4—4 of Fig. 3. Fig. 5 is a partial plan view of a modified form of engine and Fig. 6 is a section on the line 6—6 of Fig. 5.

A, is the central portion of the cylinder body, B, B, the heads having cylindrical portions which are secured to the cylinder body A so as to form continuations thereof and in which are formed a circumferential series of delivery ports indicated at B'. To the end 60 portion of the heads are formed the radial series of admission ports indicated at B'. A bearing hub B², extends upward from the center of the hub and to one side of the head is formed the supplemental hub indicated at 65 B³. Through the supplemental hub extends the shifting port B⁶ and the hub also serves as a bearing for the shaft indicated at J, and has at its inner end the crank chamber indicated at B⁴, said chamber lying outside 70 of the seat for the admission valve which is formed on the inside of the head. As shown, the head casting is formed with an inwardly projecting annular wall B⁷ which serves as one wall of the delivery chamber and it is also 75 formed with strengthening ribs as indicated at B⁸.

C, C, indicate cast heads fitting on the heads B, as best shown in Fig. 2, and constituting the outer walls of the delivery chambers, said delivery chambers being made up of an annular portion indicated at D, Fig. 4, and merging into an outlet opening indicated at D', to which openings are connected 80 the delivery pipes or reservoir.

E, is an annular valve ring fitting over the circumferential series of delivery ports and connected through a head E', with an actuating rod P², which, in turn is connected with the piston P of an actuating cylinder O, the 90 cylinder having a cylindrical extension O', in which fits an extension P' of the piston, said piston extension being made in the form of a hollow cylinder as well shown in Fig. 4 and having fitting in it a plunger Q, actuated 95 through an actuating rod Q', and crank Q², by a rock shaft Q³, which is actuated in turn through the lever arm Q⁴, by the rod extension N², of an eccentric ring N, fitting on an eccentric N', secured to a positively moving 100 shaft S. The action of the mechanism for actuating the plunger Q, is such as to cause the plunger to move toward the piston at the times when the valve E should be closed, the plunger forcing the piston inward and 105 through its connection with the valve casing, the valve. The opening of the valve is effected by the auxiliary cylinder and piston

O P in any convenient and well known manner, an ordinary plan being that indicated, namely, by connecting the cylinder O, by a pipe R with the interior of the cylinder A, 5 the valve box R', being situated in the pipe R, as shown and described in my prior patent No. 780,911, dated January 24, 1905.

F, is the compressing piston of the engine which is actuated through piston rod F', in 10 any convenient and usual manner, G, G, indicating stuffing boxes at the end of the hubs B² through which the piston rod passes.

H, is the oscillating grid admission valve which works on the inner face of the head 15 and over the radial ports B', I, indicating the circular bearing for the hub of the admission valve.

J, is a rock shaft supported in the hub B³ and having at its inner end a crank J' which 20 moves in the crank chamber B⁴ and is connected by a crank pin H' with the oscillating admission valve. The rock shaft J and the valve actuated with it as described is actuated through the lever arm J', by the eccentric N', which is connected with a lever arm, 25 as best shown in Fig. 1, the lever arm having a connecting rod K pivotally attached to a crosshead K', moving in a crosshead guide L and actuated through a connecting rod K³ 30 supported in a bearing L', said lever arm K³ being actuated by the eccentric strap N through a connecting rod K⁴. It will thus be seen that the motions of the admission both of opening and closing and of the delivery valves in closing are performed in fixed 35 and definite relationship to the movements of the engine which actuates the shaft S while the opening of the delivery valves occurs at relatively varying times, depending 40 on the pressure in the receivers.

M, is a snifting valve for closing the snifting port B⁶, and in this connection it should be noted that the admission valve is formed with a transverse slot H², see Fig. 4, which 45 registers with the snifting port B⁶ so that the valve M is always exposed to the full pressure in the compressing cylinder and is free to act at any time if the full pressure exceeds the determined amount for which the 50 valve is set to open.

While I have shown the circumferentially arranged ports as extending around the entire cylinder end and have also shown the radially arranged ports symmetrically disposed 55 about the entire heads, it will be obvious that in either case only such parts as are necessary for the desired port area need be employed.

Instead of employing an annular valve for the circumferential ports B⁵, the outer ends 60 of the latter may all terminate in the same plane as shown in Figs. 5 and 6 and be controlled by a sliding grid valve B⁹. In this form of my invention a wall B¹¹ corresponding to the wall B⁷ in the construction first 65 described may form three sides of the wall

of the delivery chamber, the other side of the chamber wall being formed by a portion of the corresponding cast head C. In this form of my invention, I have shown the cylinder wall as formed with a water jacket.

Having now described my invention, what I claim as new and desire to secure by Letters Patent is,

1. In a blowing engine or compressor, a compressing cylinder having radially arranged ports in its heads with valve seats formed on the inside of said heads in combination with oscillating valves seated on said inside seats, shafts extending through the heads and means connected to the inner ends 75 of said shafts for actuating the valves.

2. In a blowing engine or compressor, a compressing cylinder having radially arranged ports in its heads with valve seats formed on the inside of said heads and a 85 crank chamber also formed on the inside of the heads and outside of the planes of the valve seats, in combination with oscillating valves seated on said inside seats, shafts extending through the heads into the crank 90 chambers and cranks secured to the inner ends of said shafts and connected to the valves.

3. In a blowing engine or compressor, a compressing cylinder having radially arranged ports in its heads with valve seats formed on the inside of said heads, said heads having also snifting valve ports formed through them, in combination with oscillating valves seated on said inside seats and having openings formed through them to register with the snifting valve ports, shafts extending through the heads and means connected to the inner ends of said shafts for actuating the valves.

4. In a blowing engine or compressor, a cylinder having two sets of ports at each end, one set serving as admission ports and the other set as delivery ports, one set of ports at each end of the cylinder being circumferentially arranged in the cylinder wall, and the other set of ports being formed in the cylinder head, a compressing piston in the cylinder, valves for the two sets of ports, means for positively opening and positively closing the admission valves and for positively closing the delivery valves at definite points in the strokes of the compressing piston, and independent means for opening the delivery valves.

5. In a blowing engine or compressor, a cylinder having at each end a set of circumferentially arranged delivery ports in its side wall and a set of radially arranged admission ports in the cylinder head, a compressing piston in the cylinder, a delivery valve seated on the inner side of each head, a delivery valve for each set of delivery ports, means for positively opening and closing the admission valves and for positively closing the de 130

livery valves at definite points in the strokes of the compressing piston, and independent means for opening the delivery valves.

6. In a blowing engine or compressor, a cylinder having circumferentially arranged ports extending through the cylinder walls at each end and radially arranged ports formed in its heads, in combination with a receiving chamber inclosing the circumferential ports, annular valve rings fitting on the outside of the circumferential ports, oscillating valves

fitting on the inside of the heads, valve actuating cylinders for actuating the valve rings to open the circumferential ports and positively actuated mechanism for moving the rings to close said ports and for actuating the oscillating valves to open and close the radial ports. 15

GUSTAV B. PETSCHE.
